UNITED STATES PATENT OFFICE

150,187

DESIGN FOR AN AIRPLANE HANGAR

Dwen R. Younger, San Francisco, Calif.

Application January 2, 1947, Serial No. 135,892

Term of patent 14 years

(Cl. D13—1)

To all whom it may concern:

Be it known that I, Dwen R. Younger, a citizen of the United States, residing at San Francisco, in the county of San Francisco and State of California, have invented a new, original, and ornamental Design for an Airplane Hangar, of which the following is a specification, reference being had to the accompanying drawing, forming part thereof, in which

Fig. 1 of the drawing is a perspective view of an airplane hangar embodying my new design showing the doors thereof closed,

Fig. 2 is a perspective view of the airplane hangar showing the doors open,

Fig. 3 is a plan view of the hangar,

Fig. 4 is a front elevational view of the hangar, and

Fig. 5 is a side elevational view of the hangar.

I claim:

The ornamental design for an airplane hangar, substantially as shown.

DWEN R. YOUNGER.
